UNITED STATES PATENT OFFICE.

LYSANDER A. FULLER, OF STONEHAM, MASSACHUSETTS.

SLED-PROPELLER.

SPECIFICATION forming part of Letters Patent No. 282,302, dated July 31, 1883.

Application filed October 28, 1882. (No model.)

To all whom it may concern:

Be it known that I, LYSANDER A. FULLER, of Stoneham, county of Middlesex, State of Massachusetts, have invented an Improvement 5 in Propelling Sleds, of which the following description, in connection with the accompanying drawings, is a specification, like letters on the drawings representing like parts.

In a sled embodying my improvements I 10 employ means for supporting and rotating the propeller of such character that the latter, resting by gravity upon the snow or road-bed covered more or less by it, may always be free to rise and fall according to the irregularities of the snow and road-bed, such sled being provided with spring stops or brakes and steering-levers, which are combined with cranks and levers adapted to be operated by the foot of the rider of the sled.

15 My invention consists in mechanical organizations, as hereinbefore more fully set forth, and claimed at the end of this specification.

Figure 1 is a side elevation of a sled embodying my invention, and Fig. 2 a top or plan view thereof.

The frame-work A, runners a, and standards a' of the sled may be of any usual or suitable shape and material. The sled has an elevated seat, b, at each side of which are like actuating-levers, b', pivoted at b², and joined by connecting- rods b³ with oppositely-arranged cranks b⁴ of the shaft of the propeller c, the said shaft having its bearings inside its cranks s in boxes secured to a frame, d, hinged or 20 pivoted to the sled-frame at d', so that the spokes or blades of the propeller, preferably made wedge-shaped at their outer ends and shod with metal pieces to insure durability, may rest upon the snow at the rear of the sled, 25 and the propeller be free to rise and fall to adapt itself to the irregularities of the snow or road-bed covered by it as the propeller is rotated by the actuating-levers b', shown as adapted to be operated by hand. At each side 30 of the sled is a like steering-lever, g, pivoted

at g', and connected at its forward end with an arm, e', of a rock-shaft, e, having a second arm or foot-piece, g², against which the foot of the rider may be pushed to cause the rear end of the steering-lever to be thrown down in contact with the snow or road-bed at the rear of the runner. Either one or the other steering-lever may be operated at will to direct the course of the sled. The rear end of each steering-lever is normally kept elevated by a suitable spring, h, the latter also serving to keep the arms g² normally turned toward the seat b.

To stop the sled, I have provided the standards at opposite sides of the sled with ears m, (shown in dotted lines,) to receive the legs of a stopping device, m², shaped as a large staple, and having its cross bar or head exposed to the foot of the operator through a slot in the board or top A of the sled. Each leg of the stopping device has a collar, m', and below the 55 said collar and the lower ear, m, is a spiral spring, m², which normally acts to keep the stopping device elevated, as herein shown in Fig. 1. The stopping device may be pressed down into the snow or ice or earth below them 60 and stop the sled.

I claim—

1. A sled provided with propelling mechanism, spring-supported stopping devices m, 65 guiding or steering levers g, and arms e', rock-shaft e, and foot-piece g², to operate substantially as shown and described.

2. The spring-supported stopping device m, applied to a sled, and constructed and arranged substantially as shown and described. 70

3. The guiding or steering levers g, combined with the arms e', rock-shaft e, and foot-piece g², substantially as shown and described.

In testimony whereof I have signed my name to this specification in the presence of two subscribing witnesses.

LYSANDER A. FULLER.

Witnesses:

JOS. P. LIVERMORE,
BERNICE J. NOYES.
